UNITED STATES PATENT OFFICE.

JOSHUA W. JONES, OF HARRISBURG, PENNSYLVANIA; COMMONWEALTH TRUST COMPANY, EXECUTOR OF SAID JOSHUA W. JONES, DECEASED, ASSIGNOR TO JONES COMPANY, OF HARRISBURG, PENNSYLVANIA, A FIRM COMPOSED OF JOSEPH R. JONES, OF PHILADELPHIA, PENNSYLVANIA, J. MILEY JONES, ROBERT ROSS JONES, AND JOHN PAUL JONES, ALL OF HARRISBURG, PENNSYLVANIA, AND WILLIAM D. JONES, OF NEW YORK, N. Y.

COIN-HOLDER OR CHANGE-MAKER.

1,172,605.

Specification of Letters Patent.

Patented Feb. 22, 1916.

Application filed October 2, 1912. Serial No. 723,538.

To all whom it may concern:

Be it known that I, JOSHUA W. JONES, a citizen of the United States, residing at Harrisburg, in the county of Dauphin and State of Pennsylvania, have invented certain new and useful Improvements in Coin-Holders or Change-Makers; and I do hereby declare the following to be a full, clear, and exact description of the same, reference being had to the accompanying drawings, forming part of this specification, and to the figures and letters of reference marked thereon.

This invention relates to devices for holding coins in a convenient position for being withdrawn in the making of change, devices of this character being especially designed for use by street car conductors and others who are called upon at frequent intervals to return change to passengers or customers, and therefore find it desirable to have the coin holding devices supported in a convenient position on the body usually by means of a belt or other attaching appliance.

The objects of the invention are to provide an exceedingly simple device composed of but few parts, easily and cheaply assembled, but which will afford a maximum safety for retaining the coins with the capacity for permitting of their withdrawal when so desired without effort on the part of the user.

Referring to the accompanying drawings, Figure 1 is a view of a blank from which the frame as well as the top and bottom of the receptacle are formed. Fig. 2 is a perspective view of a complete holder having a single tube or receptacle; Fig. 3 is a view looking at the bottom of the holder shown in Fig. 2; Fig. 4 is a perspective view of the preferred form of spring retainer for preventing the accidental escape of coins from the bottom of the receptacle; and Fig. 5 is a sectional view in a vertical plane from front to rear of the holder shown in Fig. 2.

Similar letters of reference in the several figures indicate the same parts.

The drawings for illustrating the present invention show but a single holder such as is ordinarily adapted for containing coins

of one denomination, but it will be understood that it is customary to make use of a series of such holders arranged side-by-side, either separately on a belt or support, or combined on a single frame or base plate, each receptacle being adapted to hold coins of a certain denomination.

In accordance with the present invention, the body A of the receptacle is of tubular formation and may be conveniently manufactured from tubes of proper diameter cut into appropriate lengths and having apertures or openings formed therein as will be presently described.

The receptacle body A is secured to a suitable base piece or frame which is conveniently formed of sheet metal. The blank from which the frame or base piece is formed is preferably of the shape shown in Fig. 1, that is to say, it has a main body portion B to which one side of the receptacle body A is riveted or otherwise suitably attached, while at the upper end it is provided with a cover piece B' which is adapted to be bent down over the upper end of the tube A and suitably attached thereto, there being in this cover piece a coin entrance slot preferably formed by slitting the cover piece on a diagonal line b, and bending the edges of the slit downwardly or in a direction to project into the receptacle to thereby form the slot and also flanges which will guard the entrance opening against the accidental escape of coins through the same, should the receptacle be inverted or subjected to excessive agitation.

The lower end of the blank is formed with a central slot C and two arms C' arranged parallel to each other and adapted to be bent under the lower end of the body A of the receptacle to constitute supporting ledges upon which the coins in the receptacle will rest. These arms or ledges C' have their proximate edges substantially parallel and somewhat widely spaced apart. The finger opening between the proximate edges extends up a short distance at the back of the receptacle, as indicated at c in Fig. 5, so as to provide an opening through which the finger of the user may be brought into engagement with the rear edge of the

lowermost coin in the receptacle. At the front the body A of the receptacle is cut away at the bottom to form a coin exit or discharge opening c' which opening is of a height approximately equal to the thickness of a coin of the denomination to be held by the receptacle, and said coin discharge slot c' merges into a front opening D through which the thumb of the user may press 5 against the coins so as to hold them down during the initial movement of the lowermost coin into the discharge slot. A second opening D' is preferably provided in the front of the tube directly above the opening 10 D, through which the thumb of the user may press against the coins higher up the tube. This second opening also forms a guide for properly placing the thumb, and affords a better view of the coins in the tube. In this 15 connection it will be noted that the slot C, the coin discharge slot c' and opening D form in effect a continuous and unobstructed opening in the front lower portion of the holder, whereby a coin which is caused to 20 protrude even very slightly from the line of the coins in the receptacle may be readily grasped between the thumb and finger so as to be withdrawn and held for presentation to the passenger or customer, and even the 25 last coin remaining in the holder can be 30 readily removed.

To prevent the coins from dropping out through the discharge slot, yielding retaining means are employed being preferably 35 formed by spring arms E, lying in proximity to the opposite ends of the discharge slot C', but adapted to be sprung apart by the exit of a coin. These spring arms E are conveniently formed by the ends of wire 40 springs E' which underlie the bottom of the holder. Said arms are guided in slots F, formed in the blank, as shown in Fig. 1 to receive and guide the spring arms, as shown in Figs. 2, 3 and 5, and also form 45 stops for limiting the movement of said arms. While the springs E' may be held in place in various ways, a cheap and convenient construction is that illustrated, wherein lugs or ears G are cut from the blank at 50 the bases of the arms C' and are adapted to be bent over the rear ends of the springs so as to clamp the same firmly in place. The extremities of the arms E are bent back over the ledges C', as clearly indicated in 55 Fig. 2, thus serving as an additional guiding means for the spring arms, particularly to prevent downward movement and bringing said extremities into positions where they will not be liable to catch in the user's 60 garments or form obstructions liable to interfere with the operation of the device.

Inasmuch as it is desirable that the slot C in the bottom of the holder shall be as long and as free as possible from any 65 obstruction; for example, as shown, extending

entirely across the bottom of the receptacle, it becomes necessary to provide some means for preventing the escape of coins through said slot, if by accident or when the first coin is dropped into the receptacle, it reaches the bottom in an edgewise position. To accomplish this result without noticeably interfering with the function of the slot in permitting the finger of the user to wipe against the coin in advancing the same 70 through the discharge or exit opening, the said slot C is bridged by a very fine cross piece H, best seen in Figs. 3 and 5, said cross piece being conveniently formed of piano-wire and being preferably located at about 75 the center of the bottom of the receptacle, whereby the length of the openings both in front and in rear of the same will be less than the diameter of a coin which the receptacle is adapted to contain. This cross bar 80 H may be held in place by solder or by being suitably attached to the arms C'. In fact, it may form an integral part of said arms C', although for convenience in manufacture and in order that it may be of the 85 smallest possible cross section, it is, as above stated, preferably made of piano wire, which is exceedingly strong and hard, and therefore will be less liable to break or be worn by the coins or finger of the user. 90

For conveniently attaching the device to the body of the wearer, the frame or base piece is preferably provided on opposite sides with relatively long downwardly extending projections K, the lower ends of 100 which are turned or bent forwardly at k, while immediately below and in line with the projections K there are provided upwardly extending projections K'. A belt may be passed into the slot formed between 105 the projections and body of the frame, either by being threaded through said slot, or by being passed edgewise through the space between the proximate ends of the projections K and K'. On the other hand, if so 110 desired, the long projections K may form in effect hooks which will extend over the upper edge of a belt, or into a pocket in the garment, or hooked on the waist band of the trousers of the user. In either instance, the 115 forwardly turned end portions k serve to securely fasten the holder in place against any accidental displacement.

Having thus described my invention, what I claim as new and desire to secure by Letters Patent of the United States, is:

1. A coin holder and change maker embodying a tubular coin receptacle having a coin entrance at the top and an exit opening at the bottom extending in a plane at right 120 angles to the axis of the receptacle, there being coin supporting ledges at the bottom of the receptacle spaced apart to form an opening entirely across the bottom of the receptacle to permit the passage of the user's 125 130

finger between the ledges from the back to the front of the receptacle and the vertical walls of the receptacle being cut away to form openings at front and back above the 5 level of the coin exit opening merging freely into said opening and the opening across the bottom of the receptacle, whereby the bottom coin in the receptacle can be grasped at diametrically opposite points and extracted from the receptacle without obstruction by the coin supporting ledges.

2. A coin holder and change maker embodying a tubular coin receptacle having a coin entrance opening at the top and a transverse exit opening at the bottom, coin supporting ledges at the bottom of each side of the receptacle having between them a finger slot extending from back to front of the receptacle, and a narrow cross bar bridging said slot intermediate the ends of the same to prevent the escape of coins edgewise through the slot.

3. A coin holder and change maker embodying a tubular coin receptacle having a coin entrance opening at the top and a transverse exit opening at the bottom with a thumb opening above and merging into the exit opening, coin supporting ledges at the bottom of each side of the receptacle 30 having between them a finger slot extending from back to front of the receptacle and merging into the exit and thumb openings at the front, and a narrow cross bar bridging said slot intermediate the ends of the same to prevent the escape of coins edgewise 35 through the slot.

4. A coin holder and change maker embodying a tubular coin receptacle having a coin entrance opening at the top and an exit 40 opening at the bottom, coin supporting ledges at the bottom of each side of the receptacle, said ledges having between them a finger slot, whereby coins may be discharged

through the exit opening, and yielding retaining arms, located entirely without the 45 tubular casing and secured at the rear to the receptacle, said arms having vertical extensions at the free ends working in guide slots in the ledges, whereby they are guided and their elastic movement limited.

50

5. In a coin holder and change maker, the combination with the tubular receptacle having a coin exit opening at the bottom, of a body plate to which said receptacle is permanently secured, said plate having at 55 the top a circular slotted extension forming the top of the receptacle, integral spaced arms at the bottom forming coin supporting ledges for the receptacle below the exit opening, and projections at each edge extending parallel with the axis of the receptacle, said projections at each side being spaced apart intermediate the height of the receptacle, the downwardly extending projections having their lower ends bent for- 60 wardly.

6. In a coin holder and change maker, the combination with the tubular receptacle having a coin exit opening at the bottom, of a body plate to which said receptacle is 70 permanently secured, said plate having at the top a circular slotted extension forming the top of the receptacle, integral spaced arms at the bottom forming coin supporting ledges for the receptacle below the exit 75 opening, and projections at each edge, extending parallel with the axis of the receptacle, said projections at each side of the receptacle being spaced apart intermediate the height of the receptacle for the admission of the supporting band.
